CLAIM

The ornamental design for an ink bottle, as shown and described.

DESCRIPTION

FIG. 1 is a front, top and left side perspective view of a first embodiment of the ink bottle;

FIG. 2 is a rear, bottom and right side perspective view thereof;

FIG. 3 is a front elevational view thereof; the opposite side being a mirror image thereof;

FIG. 4 is a left side elevational view thereof;

FIG. 5 is a right side elevational view thereof;

FIG. 6 is a top plan view thereof;

FIG. 7 is a front, top and left side perspective view of a second embodiment of the ink bottle;

FIG. 8 is a rear, bottom and right side perspective view thereof;

FIG. 9 is a front elevational view thereof; the opposite side being a mirror image thereof;

FIG. 10 is a left side elevational view thereof;

FIG. 11 is a right side elevational view thereof; and,

FIG. 12 is a top plan view thereof.

The broken lines showing the shape of the bottle in the above FIGS. are for illustrative only and form no part of the claimed design.
